Everett:
Harry B. Waters.

UNITED STATES PATENT OFFICE.

HARRY BERNARD WATERS, OF DENVER, COLORADO.

SHEET-MUSIC AND LOOSE-LEAF BINDER.

1,222,500.

Specification of Letters Patent.

Patented Apr. 10, 1917.

Application filed September 18, 1916. Serial No. 120,892.

To all whom it may concern:

Be it known that I, HARRY B. WATERS, of Denver, in the county of Denver and State of Colorado, have invented certain new and useful Improvements in Sheet-Music and Loose-Leaf Binders, of which the following is a full, clear, and exact description.

My invention relates to improvements in binders that are designed more especially for binding together in pamphlet form, single copies of sheet music, which are invariably printed on one or more double sheets or pages and a single insert sheet or page.

In carrying out my invention, I have particularly in view as an object, the provision of a binder that will bind or fasten the leaves or pages of a piece of sheet-music together in pamphlet form, in such manner, so that the leaves or pages of the sheet music will practically be hinged together at the fold, so that the pages will open to the fullest extent and lie flat when opened.

A further object of my invention is to provide a binder which while fastening the leaves or pages of sheet-music together in pamphlet form, will also strengthen the pages at the fold and thereby prevent wear and tear.

With the above-recited objects and others of a similar nature in view, my invention consists in certain features of construction and in combination of parts hereinafter described and set forth in the appended claim.

In the accompanying drawings, Figure 1 shows a view of a piece of sheet-music the pages of which are bound together through the agency of my improved binder. Fig. 2 is an end or edge view showing a folded or double page and a single page of sheet-music bound together through the agency of my binder. Fig. 3 is a full view of the binder as it is constructed.

The binder is cut from any suitable, pliable material, such as cloth or leather. The binder is made to be used as a sticker having an adhesive preparation applied to the side to be fastened to the sheets or pages proposed to be bound.

A represents the body of the binder, which is cut in oblong shape, having the corners rounded. Two tongues *b' b'* are cut at approximately each end of body, extending in opposite directions from center of body of binder, said center being represented by a line drawn from *c* to *c*. When the body of binder is folded evenly at the center on a

line from *c* to *c* with the adhesive preparation on the inside, the completed binder is formed.

It will be observed that the binder, when folded, contains four divisions or leaves, the two sides of the body *A* and the two tongues *b' b'*. The four divisions or leaves are practically hinged at the center or fold of binder so that they may be turned separately the same as pages in a book.

When the binder is used to fasten the pages of a piece of sheet-music together in pamphlet form, as shown in Figs. 1 and 2, two or more binders are used. Slits *d' d'* as shown in Figs. 1 and 2 are made through the fold of the double or outside pages of the sheet-music, preferably near the upper and lower ends of the pages where the binders are to be applied, sufficiently long to admit the tongues of the binders. The tongues *b' b'* of the binder are then inserted into the slits *d' d'* from the outside of the double page as shown in Fig. 2. The body of the binder is then folded over and pasted to the upper and lower pages of the outside double page as shown in Fig. 1. As shown in Fig. 2, the tongues *b' b'* of the binder, are then pasted to the single or insert page.

When it is desired to bind a number of all double pages together by means of my improved binder, slits to admit the tongues of the binders are made evenly through the folds of all the pages and the tongues are pasted to the inside of the middle or center page. The body of the binder is folded over and pasted to the outside pages as shown in Fig. 1.

When it is desired to bind several single sheets or pages together in pamphlet form by means of my improved binder, the folds of the binders are pasted to the outside of the upper and lower pages, the tongues of the binder protruding inward between the upper and lower pages. The tongues are then pasted to the inside pages as shown in Fig. 2.

I am aware of the fact that there are a number of binders or fasteners used for the purpose of binding pages together in pamphlet form, such as wire cleats, metal clips, etc., but with none of them is it possible to bind all single sheets or both single and double sheets or pages together in pamphlet form and in such manner as will allow the pages to open fully at the folds and per-

mit the pages to lie flat when opened, as is necessary when sheet-music is placed open on a music rack.

Users of sheet-music recognize the fact 5 that the loose pages of their collection of various pieces of sheet-music often become mixed through handling and the pages easily wear and tear at the fold. The merits of my improved binder, although simple of 10 construction and inexpensive, will therefore be apparent.

While I have herein shown and described one preferred embodiment of my invention, I wish it to be understood that I do not confine myself to all the precise details of construction, as there may be modifications in 15 regard to details, without sacrificing any of the advantages thereof. For instance, the body of the binder may be of any desired

width and length and contain any number 20 of tongues that the length of the binder will allow. The binder may be used for binding together in pamphlet form loose leaves or pages of any nature, such as manuscripts, legal documents, specifications, etc. 25

Having thus described my invention, I claim as new and desire to secure by Letters Patent—

A binder or fastener composed of a single piece of pliable material, cut in oblong 30 shape, adapted to be folded evenly lengthwise, thereby forming two opposite wings and having tongues cut on opposite wings extending from the fold outwardly and having the inner faces of the wings and tongues 35 coated with adhesive.

HARRY BERNARD WATERS.
